John H. Flamm INVENTOR
Victor J. Evans ATTORNEY

WITNESS:

UNITED STATES PATENT OFFICE.

JOHN HENRI FLAMM, OF BALTIMORE, MARYLAND.

SAFETY DEVICE.

Application filed November 7, 1923. Serial No. 673,366.

To all whom it may concern:

Be it known that I, JOHN H. FLAMM, a citizen of the United States, residing at Baltimore, in the county of Baltimore City 5 and State of Maryland, have invented new and useful Improvements in Safety Devices, of which the following is a specification.

This invention has reference to a lightning protector for radio.

10 An object is to produce a device for this purpose that comprises a spring influenced slidable switch through which electric current from the aerial wire is grounded and which is movable in an opposite direction 15 upon engagement therewith of the plug to the radio set so that the current will be directed to the set and the return wire of the set automatically grounded.

10 A further object is the production of a 20 device of this character that is automatic in action, cheaply constructed and readily installed.

To the attainment of the foregoing and other objects which will be apparent as the 25 nature of the invention is fully understood, reference is to be had to the drawings which accompany and form part of this application.

In the drawings:—

30 Figure 1 is a front elevation of the improvement.

Figure 2 is a sectional view approximately on the line 2—2 of Figure 1.

Figure 3 is a similar sectional view with 35 the plug inserted to influence the switch in one direction.

Figure 4 is a sectional view on the line 4—4 of Figure 2.

Figure 5 is a sectional view on the line 40 5—5 of Figure 3.

The casing 1 of my improvement is of some suitable insulating material, and comprises a cross-shaped member. The front of the casing is open, but is closed by a suitable plate 2, also of insulating material. The elongated body portion of the casing has its ends reduced, and through these ends there are passed suitable securing elements 3.

50 In the said central portion of the casing, at the top thereof there is fixed a block 4 of copper or other electric conducting material, and on the outer face of this block, and projecting through the casing there is a binding post 5 for the aerial wire 6.

55 On the lower portion or bottom of the

said casing there is a block 7 of copper or other electric conducting material. This block has its upper face provided with a V-shaped notch 8 and its outer face provided with a binding post 9 for a ground 60 wire 10. The block 7 is in the nature of a ground terminal.

Slidable in the casing there is a switch member 11 that has its lower end pointed, as at 12 for frictional engagement with the 65 walls of the notch 8 in the ground terminal 7. The switch is influenced to such engagement through the medium of a spring 12' arranged for contacting engagement with the upper end of the said switch and the 70 lower end of the copper block 4.

The face plate for the casing has an opening 13 therethrough disposed opposite a notch in the outer face of the switch 11. The lower wall of this notch is straightened 75 and is disposed at a right angle with respect with the longitudinal plane of the said switch, but the upper wall of the said notch is arranged at an upward curvature as indicated by the numeral 14. The outer surface of the curved wall 14 is disposed opposite the opening 13 when the switch is closed, and the said wall 14 is designed for contacting engagement with the plug 15 for the 80 radio set. Before the insertion of the plug 85 the aerial wire 6 is grounded and the construction thus serves as a lightning protector. When the plug is inserted the current from the aerial wire is directed through the block 4, spring 12, switch 11 and plug 15 to the radio set.

In the lateral branches 16 and 17 of the casing 1 there are contacts engageable by switch arms carried by the main switch 11. 95 These switch or conductor arms are indicated by the numerals 18 and 19 respectively and enter the main switch through bushings 20 of insulating material. The arm 18 is engageable with a contact 21 on a binding post 22 to which is connected the ground wire from the radio set, indicated by the numeral 23. The second arm 19 is engageable with a contact 24 on a binding post 25. To the binding post there is connected a conductor wire 26 which is also connected to the ground terminal or fixed switch member 7. The circuit maker, just described is brought to operative position only when the plug 15 is inserted to bring the slidable switch element 11 out of engagement with 100 105 110

the fixed switch element or ground terminal 7.

My improvement eliminates the need of grounding the radio set in the usual manner. 5 The device is automatic in action, depending only upon the insertion of the plug when the radio set is required for use. The elements 18 and 19 are insulated by the bushing 20 from the switch 11 so that liability 10 of short circuiting the circuit maker is thus overcome. The device is of a simple construction, may be readily fixed upon any convenient support, and while I have shown and described a satisfactory embodiment of 15 the improvement as it now appears to me, it is to be understood that I may make such departures therefrom as fairly fall within the scope of what I claim.

Having described my invention, I claim:— 20

A switch comprising a stationary contact, a movable contact having a recess therein adapted to cooperate with said stationary contact, a second switch having a plurality of stationary contacts, a bar carrying a plurality of movable contacts adapted to cooperate with said stationary contacts, said bar being carried by but insulated from the movable contact of the first switch, a plug 25 adapted to be connected to a translating device and adapted to engage said recess and operate said movable contact. 30

In testimony whereof I affix my signature.

JOHN HENRI FLAMM.
